UNITED STATES PATENT OFFICE

122,687

DESIGN FOR A PORTABLE SERVING CABINET

Herman Kranz, Los Angeles, Calif.

Application November 6, 1939, Serial No. 88,082

Term of patent 3½ years

To all whom it may concern:

Be it known that I, Herman Kranz, a citizen of the United States, residing in the city of Los Angeles, county of Los Angeles, State of California, have invented a new, original, and ornamental Design for a Portable Serving Cabinet, of which the following is a specification, reference being had to the accompanying drawing, forming part thereof.

Figure 1 is a front perspective view of a portable serving cabinet, with the door in closed position, showing my new design, and

Figure 2 is a front perspective view thereof, with the door in an open position.

The rear of the article is substantially plain.

I claim:

The ornamental design for a portable serving cabinet, as shown and described.

HERMAN KRANZ.
